UNITED STATES PATENT OFFICE.

RICHARD WALDRON, OF BRIGHTWOOD, DISTRICT OF COLUMBIA.

DESIGN FOR A JEWEL-CASE.

42,658.

Specification for Design.

Patented June 18, 1912.

Application filed March 30, 1912. Serial No. 687,508. Term of patent 7 years.

To all whom it may concern:

Be it known that I, RICHARD WALDRON, a citizen of the United States, residing at Brightwood, in the District of Columbia, have invented a certain new, original, and ornamental Design for Jewel-Cases, of which the following is a specification, reference being had therein to the accompanying drawing.

Figure 1 is a top plan view of the design of my jewel case. Fig. 2 is a bottom plan view thereof. Fig. 3 is a view of the back thereof. Fig. 4 is a view of the front.

In use it is intended that the ornamental

side shown in Fig. 1 shall be kept uppermost during the day and the side shown in Fig. 2 kept uppermost during the night to deceive burglars.

I claim:—

The ornamental design for a jewel case as shown and described.

In testimony whereof I hereunto affix my signature in presence of two witnesses.

RICHARD WALDRON.
